UNITED STATES PATENT OFFICE.

HENRY FRANKLIN McLEY, OF PATTONSBURG, MISSOURI.

CATTLE-GUARD AND SIGNAL.

1,249,796.

Specification of Letters Patent. Patented Dec. 11, 1917.

Application filed February 21, 1917. Serial No. 150,099.

To all whom it may concern:

Be it known that I, HENRY FRANKLIN McLEY, a citizen of the United States, residing at Pattonsburg, in the county of Dade, State of Missouri, have invented a new and useful Cattle-Guard and Signal; and I do hereby declare the following to be a full, clear, and exact description of the invention, such as will enable others skilled in the art 10 to which it appertains to make and use the same.

This invention relates in general to cattle guards and is particularly a guard of this character to be used at railroad crossings.

15 Its principal object is to provide a guard having gates at each side of the highway which the track crosses that can be moved out of the way of a moving train by means carried by the train.

20 A second object is to provide a double gate cattle guard that can be folded down in either direction against the track and that is capable of being operated by trains passing in either direction.

25 A third object is to provide such a guard as can be applied without the necessity of departing from the conventional form of track construction at the point where it is installed.

30 A fourth object is to provide for the attachment of a signal that will be operated simultaneously with the guard by the same means that operates the guard.

In setting forth this invention, no pretense 35 is made to mechanical refinement. The concomitant parts of the device are made disproportionately large in order to more clearly illustrate their operation.

The uniform system of designating the 40 parts obtains in all of the several figures of the drawings, wherein;

Figure 1 is a plan of the invention.

Fig. 2 is a side elevation of the same.

Fig. 3 is a section on the line 3—3 of

45 Fig. 1.

Fig. 4 illustrates the same parts as Fig. 3, but the gates are shown in their lowered position. This figure also shows in dotted lines the reversed position of the gates at the moment of being released after a train has passed.

Fig. 5 is a section on the line 5—5 of Fig. 1.

Fig. 6 is a section on the line 6—6 of Fig. 1.

Fig. 7 shows the same parts as Fig. 6 but in their lowered position. 55

Fig. 8 is a perspective view of the catch 33.

Fig. 9 is a perspective view of the rocker arm 41.

Fig. 10 is a perspective view of the connecting rod 44. 60

This invention is illustrated as applied to a road-bed having the ties 1 to which are attached the rails 2. Between a pair of ties at one side of the railroad crossing and a similar pair of ties at the other side of the crossing, the gates 3 are pivotally mounted by means of bracket bearing members 4 secured to the upper faces of adjacent ties by means of appropriate bolts or lag-screws. 70

As integral parts thereof, the gate 3 has the transverse rod 4, the shaft member 5, the U-shaped crank 6 and the narrow gate member 7. A bifurcated upturned end 8 is adapted to receive one end of the spring 9, a pin 10 effecting the connection between the two. Columns 11 and 12 are positioned directly above the upturned ends 8, one column being stationed on one side of the highway and the other on the opposite side. These 80 columns are circular in section and are supported by their spreading legs that terminate in circular bosses 14 by which the columns 11 and 12 are attached to the ties by means of appropriate bolts or lag-screws. 85

Both columns 11 and 12 are hollow, holes extending from the crotches between the legs to their tops. In the case of the column 11, the spring 9 extends up into the interior and is secured therein by pin 15 which passes 90 through and is frictionally held in holes formed in the walls of the column. In the case of the column 12 the spring 9 connects with a rod member 16 that is in pivotal engagement at its upper end with the tail of a signal 17. This signal is pivoted between the arms 18 which are integral parts of the column 12. 95

Outside of the rails 2 and on the same side of the track as the columns 11 and 12 are the throw-bars 19. At one end they are in pivotal engagement with the cross bars 21 of the narrow gate 7 that are on their side of the track. This pivotal engagement is ef- 100

fected by means of the heads 20 which are separable into halves to permit their attachment, suitable cap-screws holding the two halves together. At the end remote of 20 the 5 throw-bars 19 are formed into the peculiar shape shown in Figs. 2, 6 and 7, the rounded end 22 abutting the semi-circular cam member 23, when the bars 19 are in their normal position. The cam member 23 is attached to 10 one of the ties by having its integral spiked projection 24 driven thereinto and the guide plates 25 are attached, one on each side of the cam member by means of an appropriate bolt 26 which passes through all three. The 15 circular slots 27 are formed in the plates 25 and a pin 28, held frictionally in the enlarged end of the throw-bar 19, moves in the slots. The radius of these slots is equal to the distance between the center of the shaft 20 5 and the center of the cross-bar 21. This arrangement permits the throw-bar 19 to be maintained parallel with the track throughout its whole movement. The throw-bar 19 is curved on the under surface where it 25 blends into the enlarged ends, this curving permitting the round projection 22 to move on either side of the cam member 23. A projection carried by the locomotive and narrow enough to pass freely between the plates 25 30 is adapted to contact with the enlarged end of the throw-bar and force it down, as shown in Fig. 7. In the drawings this projection is shown as a pivotally supported roller 29. The description of the throw-bar 35 19 has been made in the singular but it applies equally to the other throw-bar on the opposite side of the crossing.

Connecting rods 30 connect the crank-members 6 of the two gates 3 and serve to 40 transmit to one gate and its attendant parts the movement imparted to the other gate. These rods connect pivotally with the crank members 6 and the pivotal engagement is effected by means of the heads 31 which are 45 similar to the heads 20 of the throw bars, being separable into halves to permit their attachment.

Attached to one of the ties by an appropriate means is an angle plate 32 and this 50 has pivotally mounted on it a catch 33 with a projection 34 emanating from its side and a similar projection 35 emanating from its back end. Projection 34 connects with a spring 36 that attaches also to a pin 37 fixed 55 in the tie. The top edge of the catch is tapered and below this tapered edge a recess 38 is formed, in which the cross rod 40 engages when the gate 3 is lowered. The protuberance 39, when the catch is vertical, 60 abuts the tie and retains the catch in a vertical position against the tension of the spring 36. Pivoted on a tie close to the one carrying the catch is a rocker arm 41 whose one end is connected to the catch by a spring

rod 42 and whose other end connects with 65 the lever 43 through the medium of the connecting rod 44. The rod 44 engages the rocker arm pivotally between the bifurcations 45, there being some vertical freedom of movement of the pivotal point to permit 70 the rod to assume an angular position when operating the catch. Where the rod 44 engages the lever 43, it is cut away leaving a projection 46 through which pivotal engagement is effected with a similar projection 47 75 formed on the lever 43. For the attachment of 43 two angle plates are provided. These are fixed to the tie by any appropriate means and support 43 between them at the pivotal point 49.

The drawings show a roller 50 adapted to be carried by the rear car of a train and designed to contact with the lever 43 to release the gates 3 after they have been thrown down by the roller 29 carried by 80 the engine.

The normal position of the mechanism is that shown in Figs. 1 and 2, this position being maintained by the spring 9 in column 11 and partly by spring 9 in column 12 85 where the weight of the signal applies some pull to the spring. An approaching train has a device (similar to roller 29) which is carried by the locomotive. This device impinges on the throw-bar 19 and moves it 90 forward causing it to assume the position shown in Fig. 7. The gate 3 and narrow gates 7 being integral parts of a whole and the throw-bar being connected with one of the narrow gates 7, the gate 3 and all its attendant parts are thus thrown down toward the track by the forward movement of the throw-bar. But the two gates are linked together, hence the movement imparted to one will be transmitted to the other, therefore, when the throw-bar is moved forward both gates will be lowered and the opposite throw-bar will assume a position with respect to its cam 23 the opposite of the throw-bar that effected the operation. The slots 95 27 would be sufficient to properly guide the throw-bar in its movement but the cam is provided to relieve the slots of undue strain at the moment of impact of the roller 29 with the throw-bar. The lowering of the 100 gates 3 is effected against the tension of spring 9 in column 11 and the similar spring 9 in column 12 operates (through the rod 16) to raise the signal 17. At their lowest 105 positions one of the gates 3 has its cross bar 40 engage in the recess 38 of one of the latches 33 where it remains and keeps both gates lowered until the train has passed when a device on the rear car (similar to roller 50) contacts with and moves the lever 110 43 causing it to move the latch (through its various connections with the latch) and release the gates which the spring 9 in column 115 120 125

11 then operates to restore to their normal positions. When the gates are lowered in one direction, the latch 33 and lever 43, on the same side with the throw-bar that effected the lowering, remains inactive, but the lever is required to yield to permit the passage of the device that effects the releasing of the gates through the opposite lever 43. The inactive lever is required to move in a direction the opposite of its normal movement and, as the movement of the latch to a reverse position is prevented by the protuberance 39, the lever 43 yields by bending the spring rod 42.

15 The lowering and release of the gates can be effected on either side of the highway crossing, thus making it possible to operate them by trains moving in either direction.

What is claimed is:

20 1. In a cattle guard and signal, gates on either side of a highway crossing and across a railroad track, pivotal supports for said gates, said gates having shaft members with crank members attached thereto, connecting rods connecting the crank members of opposite gates, throw-bars separately engaging a crank member of each gate and adapted to be moved longitudinally by means affixed to the locomotive to effect the lowering of the gates, guide plates for the throw-bars, pin members for the throw-bars, circular slots in the guide plates in which the pin members are adapted to slide, cam members between the guide plates, projections on the throw-bars and adapted to abut the cam members when the throw-bars are in their normal position, means for releasing the gates, a signal, connections between the gates and the signal for the simultaneous operation of the signal, and a spring tensioning means for restoring the gates to their normal position after release.

2. In a cattle guard and signal, gates on either side of a highway crossing and across a railroad track, pivotal supports for said gates, said gates having shaft members with crank members attached thereto, connecting rods connecting the crank members of opposite gates, throw-bars separately engaging a crank member of each gate and adapted to be moved longitudinally by means affixed to the locomotive to effect the lowering of the gates, guide plates for the throw-bars, pin members for the throw-bars, circular slots in the guide plates in which the pin members are adapted to slide, cam members between the guide plates, projections on the throw-bars and adapted to abut the cam members when the throw bars are in their normal position, a spring operated catch for retaining the gates in their lowered position, means adapted to be operated by a device carried on the rear car of the train for operating the catch to release

the gates, a signal, connections between the gates and the signal for the simultaneous operation of the signal, and a spring tensioning means for restoring the gates to their normal position after release. 65

3. In a cattle guard and signal, gates on either side of a highway crossing and across a railroad track, pivotal supports for said gates, said gates having shaft members with crank members attached thereto, connecting rods connecting the crank members of opposite gates, throw-bars separately engaging a crank member of each gate and adapted to be moved longitudinally by means affixed to the locomotive to effect the lowering of the gates, guide plates for the throw-bars, pin members for the throw-bars, circular slots in the guide plates in which the pin members are adapted to slide, cam members between the guide plates, projections on the throw-bars and adapted to abut the cam members when the throw-bars are in their normal position, spring operated catches for retaining the gates in their lowered position, levers pivotally mounted on the ties and adapted to be operated by a device carried on the rear car of the train, rocker arms pivoted on the ties, connecting rods between the levers of the rocker arms, connecting rods between the rocker arms and the catches, a signal, connections between the gates and the signal for the simultaneous operation of the signal, and a spring tensioning means for restoring the gates to their normal position after release.

4. In a cattle guard and signal, gates on either side of a highway crossing and across a railroad track, pivotal supports for said gates, said gates having shaft members with crank members attached thereto, connecting rods connecting the crank members of opposite gates, throw-bars separately engaging a crank member of each gate and adapted to be moved longitudinally by means affixed to the locomotive to effect the lowering of the gates, guide plates for the throw-bars, pin members for the throw-bars, circular slots in the guide plates in which the pin members are adapted to slide, cam members between the guide plates, projections on the throw-bars and adapted to abut the cam members when the throw-bars are in their normal position, spring operated catches for retaining the gates in their lowered position, levers pivotally mounted on the ties and adapted to be operated by a device carried on the rear car of the train, rocker arms pivoted on the ties, connecting rods between the levers of the rocker arms, connecting rods between the rocker arms and the catches, a signal, a spring tensioning means connected with one of the gates for restoring them both to their normal positions after release, a similar spring tensioning 100 105 110 115 120 125

means connecting the other of the gates with the signal, a hollow column attached to the ties and supporting the signal, and a similar hollow column attached to the ties for supporting the spring means that restores the gates to their normal position.

In testimony whereof I have signed my

name to this specification in the presence of two subscribing witnesses.

HENRY FRANKLIN McLEY.
